UNITED STATES PATENT OFFICE.

JOHN MERCER, OF NEW BRIGHTON, ENGLAND.

APPARATUS FOR TREATING SMOKE AND FUMES.

1,121,746.

Specification of Letters Patent. Patented Dec. 23, 1914.

Application filed May 20, 1912. Serial No. 698,474.

To all whom it may concern:

Be it known that I, JOHN MERCER, a subject of the King of England, residing at 8 Magazine Lane, New Brighton, in the county of Chester, England, have invented certain new and useful Improvements in Apparatus for Treating Smoke and Fumes, of which the following is a specification.

This invention relates to a method of and 10 apparatus for conducting combustion in furnaces with the objects of effecting more perfect combustion of fuel and consumption of smoke.

It has, heretofore, been proposed to 15 turn to a furnace the whole or a part of the gases of combustion mixed with atmospheric air, by the aid of a fan or blower or the like, said air being induced into the flue or conduit system by means of said fan or 20 blower.

The present invention consists essentially 25 in circulating the gases of combustion by means of a fan, blower, or its equivalent; permitting the heavier non-combustible gases to escape under the influence of gravity; permitting the atmospheric air or oxygen for supporting combustion—by admixture with the lighter and more combustible gases—to enter the flue or conduit system 30 only by way of the orifice or orifices through which said heavier gases are issuing, providing means whereby said heavier gases are withdrawn on discharge from said opening or openings and separate means 35 whereby atmospheric air is admitted to said opening or openings.

Preferably, a chamber of special construction is provided in the flue or conduit system to facilitate the separation and 40 escape of said heavier gases from the lighter gases, and the diffusion therethrough of the fresh air or oxygen.

I believe, from experimental practice, 45 that the oxygen only, or oxygen with a comparatively small percentage of nitrogen, of the air, passes by diffusion through said escaping heavier gases of combustion into said flue or conduit.

In order to show more clearly the nature 50 of this invention, I have hereinafter described and illustrated its application in a simple diagrammatic form, for the treatment of smoke, fumes, and other volatile products formed during the combustion of 55 fuel such as coke or coal in an ordinary

furnace, for the purpose of heating a closed or muffled-oven.

Of the accompanying drawings, Figure 1 shows, in diagrammatic form a sectional elevation of a closed muffled-oven to which my invention is applied. Figs. 2 and 3, are sectional-side and end-elevations in outline, of another form of diffusion-chamber which is part of my invention.

In Fig. 1, a body of fuel C, is supplied by the hopper H², for the purpose of heating the oven K. The smoke, fumes, and other volatile gas or products L, W, given-off from the burning fuel C, passing through the flues H, H¹, being induced or otherwise circulated through the said flues, by any suitable means, such as a fan, P, or the like, which creates and maintains a current circulating from the fuel C, through the flues H, H¹, to the diffusion-chamber B, and thence through the body of fuel C.

The diffusion-chamber B, which may be formed with closed top and sides of any convenient form, is provided with suitable openings b¹, b², for the admission and emission of the said volatile products, respectively. The bottom or lower portion b³, of the said chamber B, is open and accessible to the atmosphere. The said diffusion-chamber is preferably placed for convenience over a pit or well A, to which atmospheric air can be admitted by means of a valve or damper R, the said pit also forming a receptacle for the heavier portions W, of the said volatile products emitted from the said chamber B. A chimney or other suitable means is provided for withdrawing the emitted products from the well A, and for distributing such waste-products to the atmosphere or elsewhere, as may be required.

When the fuel C is ignited, the smoke, fumes and other volatile products of combustion L, W, given-off therefrom, are conveyed along the flues H, H¹, by means of the current produced by the fan P, through the opening b¹, into the diffusion-chamber B, where the said volatile products or gases L, W, re-arrange themselves, the heavier and incombustible portions of the said products W, being emitted from the lower portion b³, of the said chamber B, into the well A, and drawn thence to the chimney D.

A supply of atmospheric air, or oxygen O, necessary to promote the combustion of

the fuel C, passes through the open bottom b³, of the diffusion-chamber B, into the interior of the said chamber, by diffusion, and in passing through the waste-products W, 5 abstracts a portion of heat therefrom. The heated air or oxygen O, and the lighter and more combustible portions of the volatile products which have remained in the chamber B, are then drawn, by means of the fan P, through the opening b², and the body of fuel C, to further assist in the combustion of fuel.

The above process, which is continuous, 10 may be accelerated or retarded by regulating the supply of fuel; the amount of air or oxygen supplied; or by regulating the speed of the fan or other current producer.

It is obvious that the draft of the chimney D, used for abstracting the waste-products, must not exceed the draft of the fan or blower P, and means such as the damper or valve E, are provided to adjust the chimney draft.

Figs. 2 and 3 illustrate, in a modified 15 form, another method of arranging the diffusion-chamber B; the well A, being, in this instance, continued around the top of the chamber B, and the chimney D, arranged on the top-side of the well A. The waste-products W are emitted from the open bottom of the chamber B, and are withdrawn through the opening b⁴, around the outside of the said chamber B, to the chimney D, whose draft can be regulated by the damper E.

In like manner the other essential parts 20 of my invention may be modified to suit the various conditions for which my invention is applicable, and although I have described my invention as applied to one simple form of oven, I would have it understood that its application is not confined to that particular purpose, but may be modified and applied in any suitable form, for the purpose and means of treating

smoke, fumes, and other volatile products of 45 combustion, without departing from the essential features of this invention.

Having now described my invention, what I claim as new and desire to secure by Letters Patent is:—

1. The combination with an oven having a flue extending around walls thereof, a fire chamber at an end of said oven in communication with the flue thereof, means at the opposite end of said oven adapted to maintain a circulation of gaseous products of combustion in said flue and through said fire chamber, a diffusion chamber in communication with the flue of said oven and having an opening in a wall thereof, and means in communication with the opening of said chamber whereby air is simultaneously admitted to the flue of said oven and heavy gases of combustion withdrawn therefrom.

2. The combination with an oven having a flue extending around the walls thereof, a fire chamber at one end of said oven in communication with the flue thereof, means at the opposite end of said oven adapted to 70 maintain a circulation of gaseous products of combustion in said flue and through said fire chamber, a diffusion chamber below said oven and in communication with the flue thereof, said diffusion chamber having the 75 bottom thereof provided with an opening, and a well structure in communication with the opening of said diffusion chamber and having provision for simultaneously admitting air to said diffusion chamber and extracting heavy gases of combustion therefrom.

In testimony whereof I affix my signature in presence of two witnesses.

JOHN MERCER.
